UNITED STATES PATENT OFFICE.

LEWIS M. COOK, OF NEENAH, WISCONSIN.

SNAP-HOOK.

SPECIFICATION forming part of Letters Patent No. 546,226, dated September 10, 1895.

Application filed February 19, 1895. Serial No. 538,949. (No model.)

To all whom it may concern:

Be it known that I, LEWIS M. COOK, a citizen of the United States, residing at Neenah, in the county of Winnebago and State of Wisconsin, have invented a new and useful Improvement in Snap-Hooks, of which the following is a specification.

My invention relates to an improvement in snap-hooks for general use upon different parts of harnesses, and upon ropes, chains, and all places for which the use of snap-hooks are adapted; and the object of my improvement is to adapt the hook for engagement and disengagement with ease and without requiring the use of the individual fingers of the person using it, the snap-hook only requiring to be grasped in the hand and a forcible movement of the snap-hook made lengthwise of it and toward or from the part to be connected with it, whereby the improvement is particularly adapted for use in the dark or when the hand of the person using it is encumbered with a glove or mitten. I attain these objects by means of the construction of the snap-hook which is shown in the accompanying drawings, in which—

Figure 1 is a top view of the snap-hook with the end broken. Fig. 2 is a side elevation thereof, the hook being complete. Fig. 3 is a side elevation, the central portion of the body of the snap-hook being in section vertically upon the line *a a* of Fig. 1; and Fig. 4 is a like view of said central portion, showing a modification in its construction.

Similar figures of reference indicate like parts in the several views.

1 indicates the body of the snap-hook; 2, a loop for its connection with a strap or other part with which it may be desired to permanently attach it; 3, a loop at the opposite or hook end for the temporary connection with it of a ring, harness-bit, or other like part; 4, a slot which is formed in the body of the hook; 5, a three-armed spider which is pivoted for revolution within the slot; 6, a spring arranged within the slot; 6', a pin for holding said spring in position therein; 7, a removable piece for covering the opening to the slot upon the back or lower side of the snap-hook in Fig. 3; 8 8', screw-holes in which screws may be inserted for connecting the piece 7 and spring 6 to the body of the hook.

The snap-hook 1, the spider 5, and also the removable piece 7, if the construction shown in Fig. 3 is used, may be cast of a suitable metal and fitted together, the spring 6 being bent of the proper form for its suitable action upon the arms of the spider 5. In Fig. 3 the spring is provided with a hole corresponding in position with the hole 8 or 8', through which a screw may be inserted for holding the spring securely, the same screw also serving to secure one end of the piece 7 to the body of the hook. The modification, Fig. 4, being used, the spring is held within the pocket by means of a pin 6'. By closing the bottom of the slot and thereby forming a pocket, and locating the pocket directly under the end of the hook 1', it is more difficult for foreign substances to enter and clog the spring and spider than it would be if the slots were open and exposed on both sides, as where they are located in the shank instead of the body of the device.

The spider is arranged for revolution within the slot upon the pivot 5' with two of its arms (excepting when a connection or disconnection is being made) arranged to bear upon the free end of the spring, whereby the third arm of the spider will extend upward and obstruct the passage between the body or swell of the hook which is around the spider and the end 1' of the hook. As one of the arms of the spider will always extend upward toward the end 1', (excepting when the spider is being turned around upon its pivot for the entrance to the loop of some article or for its removal therefrom,) nothing can enter or leave said loop without the application of sufficient force to said arm to revolve the spider one notch—*i. e.*, until this arm is turned down against the spring and another one takes its place. By making the spider with three similar arms and locating them equidistant from each other, as above described, it is free to rotate in either direction, and it is not necessary to insert it in any particular manner, as must be done with a two-armed spider, and after it has been inserted, as many attachments can be made with the one hook, as desired, by simply rotating the spider until all of the attachments have been made, as where it is desired to place two or more rings in the hook, and the attachments can be discon-

connected by simply rotating the spider in the opposite direction, which could not be done with a two-armed spider which oscillates upon its pivot instead of rotates.

5. By providing a spring of the proper stiffness the hook can be adapted for heavy or light uses, whereby a slight pull or push upon the hook will connect or disconnect the same from the ring or other article with which it may be connected.

I do not confine my invention to the use of a spring of the identical form herein shown, as many forms and material for said spring may be used which will effect the desired result.

The slot 4 is covered upon the outside of the body of the hook, protecting the spring and the slot around it from the entrance of snow, ice, dirt, &c., and thereby providing for the free and easy working of the spider and spring.

Having described my invention, what I claim, and desire to secure by Letters Patent, is—

25. 1. A snap hook, the upper surface of the body of which is provided with a pocket, and the hook portion extends up over and forms a cover for the same, a spring within the

pocket, and a spider pivotally secured within the pocket above the spring, said spider having three similar arms equi-distant from each other and of the same length, two of said arms being adapted to bear against the spring and the remaining one projects above the upper surface of the body adjacent to the hook, substantially as set forth.

2. A snap hook, the body of which is provided with a slot and the hook portion extends up over the slot and forms a cover for the same, a removable piece over the pocket upon the opposite side of the body, a spring within the slot, one end of which is located between the body and one end of the removable piece, and a three armed spider pivotally secured within the slot above the free end of the spring, said arms being equidistant from each other and of the same length, two arms of which are adapted to rest against the spring and the other arm is adapted to project beyond the surface of the body adjacent the hook, substantially as set forth.

LEWIS M. COOK.
